[57] CLAIM

The ornamental design for a wheeled case, as shown and described.

DESCRIPTION

FIG. 1 is a perspective view of case;
FIG. 2 is a top plan view thereof;
FIG. 3 is a front elevation thereof;
FIG. 4 is a right-hand side elevation thereof;
FIG. 5 is a left-hand side elevation thereof;
FIG. 6 is a rear elevation thereof;
FIG. 7 is an underside plan view thereof;
FIG. 8 is a perspective view thereof corresponding to FIG. 1, but with the front flaps in an open position;
FIG. 9 is a perspective view corresponding with FIG. 6, but with the top flaps in an open position; and,
FIG. 10 is a perspective view of a modified embodiment of the wheeled case of FIG. 1, wherein the handle is shown in an extended position.

The broken line portions of FIGS. 8-10 are for illustrative purposes only and form no part of the claimed design.
